Primary Examiner — Mitchell Siegel(74) Attorney, Agent, or Firm — Banner & Witcoff, Ltd.(57) CLAIM

The ornamental design for a golf club head, as shown and described.

DESCRIPTION

FIG. 1 is a perspective view of a golf club head showing my new design;

FIG. 2 is a bottom view thereof;

FIG. 3 is a heel end view thereof;

FIG. 4 is a toe end view thereof;

FIG. 5 is a front view thereof;

FIG. 6 is a rear view thereof; and,

FIG. 7 is a top view thereof.

The broken lined border immediately adjacent to the claimed area representing unclaimed boundaries is for environmental purposes only and forms no part of the claimed design.
